AIRPLANE TOW TARGET RELEASE DEVICE

Alan E. Brickman, New Haven, Conn., assignor to
 The American Steel and Wire Company of New
 Jersey, a corporation of New Jersey

Application January 22, 1944, Serial No. 519,385

11 Claims. (Cl. 273—105.4)

This invention relates to airplane tow targets, and particularly, to an improved means or device for releasing targets towed by aircraft for use in gunnery practice.

It is now common practice to employ a release device on the end of a target tow cable for replacing the used target being towed with a new target. In order to replace the target being towed with a new target, the latter target which is folded and secured by a rip cord, is secured to a ring placed on the tow line and launched from the plane. The ring is threaded onto the tow cable and the forward motion of the plane draws the tow cable and release device through the ring until the ring strikes a projecting portion usually carried by the release device. The resultant jerk releases the rip cord and the target opens up due to the wind velocity and is in tow. After a predetermined amount of target shooting, a new target, in bundled form, is launched in the same manner. As the ring passes over the releasing device, it depresses usually a trigger arrangement which in turn withdraws the projecting portion to which the ring of the spent target is attached and the ring passes off the release device and the target releases it from tow and it falls to the earth for recovery and scoring.

Various types of release devices have been heretofore suggested and used. One of the most common types used consists of a longitudinally extending rather heavy cylindrical body member having a trigger and hook release mechanism. Such a release device has been found to be unsatisfactory for several reasons. In the first place, the ring member of the replacement target oftentimes sheared the tow cable at a point immediately next to the heavy body member due to the speed at which the ring passes over the tow cable and the weight of the release mechanism. Also, a heavy release device or assembly tends to whip about on the end of the tow cable and oftentimes, the ring of the replacement target passes over the trigger without releasing the spent target and, at other times, both the new target together with the spent target would pass completely over and off the release device with the result that there was a loss of a target and that no target was in tow. Thus, it will be seen that the use of such a release device not only resulted in damaging the tow cable but also resulted in loss of the target at times, and delay or incompletion of gunnery practice.

Accordingly, it is the general object of the present invention to provide an improved tow

target release device whereby all of the above mentioned disadvantages are eliminated.

It is another object of this invention to provide an improved tow target release device which is relatively light in its construction, and, substantially foolproof in its use so as to insure the replacement of a spent target with a new target.

It is a further object of this invention to provide an improved tow target release device which is simple and inexpensive in its construction, and, at the same time, efficient and effective in its use.

Various other objects and advantages of this invention will be more apparent in the course of the following specification and will be particularly pointed out in the appended claims.

In the accompanying drawing there is shown, for the purpose of illustration, an embodiment which my invention may assume in practice.

In the drawing:

- 20 Figure 1 is a side elevational view of the outer end of an airplane tow target cable in tow, showing the improved release device of my invention incorporated therewith together with a tow target connected thereto;
- 25 Figure 2 is an enlarged side elevational view of my improved release device showing the parts thereof in their releasable position;
- 30 Figure 3 is an enlarged side view of the outer end of my improved release device; and
- 35 Figure 4 is a sectional view taken on line IV—IV of Figure 3.

Referring more particularly to the drawing, there is shown in Figure 1, a target tow cable 2 having the inner end thereof attached to an aircraft. On the outer end of the tow cable, there is arranged a connecting member 3 having an eye portion 4 to which the improved release device 5 of the present invention is pivotally connected in a manner hereinafter to be described. On the outer end of the release device 5, there is releasably connected thereto, a target lead cable 6 having a traveler ring 7 arranged on the inner end thereof by which it is attached to the release device, and on the outer end of the lead cable, there is disposed a target 8.

The improved release device 5 of the present invention, as more clearly shown in Figures 2, 3 and 4, comprises a resilient metallic member, preferably made of round wire, which is bent upon itself so as to provide a longitudinally extending body member having a substantially U-shaped portion 9 arranged on one end thereof with the free ends 10 and 12 of the same being normally spaced from each other due to the resiliency thereof. On the outer side of the outer

end of the free end 10, there is disposed an enlarged portion 13 which is preferably formed by bending the end of the free end into the form of a hook and inserting an irregular-shaped member or slug 14 in the hook portion, as more clearly shown in Figure 3 of the drawing. The insert member 14 is preferably welded in position in the hook portion so as to be securely held therein and constructed so as to entirely fill the same. Intermediate the length of the free end 10, there is arranged an outwardly extending or cam portion 15. In other words, the free end 10 is preferably bent so as to form a cam portion on the outer side thereof intermediate the length of the same.

The outer end of the opposed free end 12 is bent inwardly and outwardly so as to provide an angular or, preferably an arcuate-shaped portion 16 adjacent the end thereof. On the extreme outer end of the free end 12 beyond the arcuate-shaped portion 16, there is arranged a longitudinally extending finger-like portion 17 which is disposed beyond the enlarged portion 13 of the free end 10.

There is attached to the free end 12 at a point adjacent the arcuate-shaped portion 16 thereof, preferably an inwardly extending metallic U-shaped member 18 with the extreme ends of the free ends of the U-shaped members disposed to either side of the free end 12 and secured thereto preferably by a ball and peen connection as at 19. The U-shaped member 18 straddles the opposed free end 10 and is positioned between the cam portion 15 and the enlarged portion 13 carried thereby. By providing such a construction, it will be seen that the free end 10 is movable relative to the opposed free end 12 together with the U-shaped member 18 carried thereby. The free end 12 preferably has a cam portion 20 arranged therein at a point immediately forwardly of the U-shaped member 18 for a purpose later to be described. The sides of both free ends 10 and 12 at a point opposite the U-shaped member 18 are preferably flattened as at 21 so as to provide an area of greater bearing surface for the U-shaped member 18.

The improved release device of my invention functions in the following manner. It will be assumed that a target is in tow and under such conditions, the tow cable, the release device and the tow target will assume the position, as shown in Figure 1 of the drawing. It will be seen that the U-shaped portion 9 of the release device 5 is positioned in the eye 4 of the connection 3 on the end of the tow line so as to be pivotally attached thereto. When the target is in tow, it will be seen that the traveler ring 7 of the target is disposed on the outer end of the release device so that one side thereof rests upon the outer or upper side of the U-shaped member 18 and abuts against the enlarged portion 13 of the free end 10 of the body member and the opposite side of the traveler ring abuts against the finger-like portion 17 of the free end 12. In other words, the enlarged portion 13 and the finger-like portion 17 are disposed diametrically opposite each other within the traveler ring 7 and rest against the inner periphery of the ring. It will be understood that in order to maintain the traveler ring on the end of the release device in such a manner, that the distance between the inner side of the enlarged portion 13 and the outer end of the finger-like portion 17 is greater than the inner diameter of the traveler ring 17.

As shown in Figure 1 of the drawing, after a

sufficient amount of gunnery practice has been had with a target in tow, and it is desired to replace this spent target with a new target, the traveler ring 7 of a new target in bundled form 5 is threaded at the aircraft onto the tow cable 2, and the traveler ring 7 together with the new target 8 attached thereto passes back over the tow cable and over the connection 3 onto the release device 5, as shown in the broken lines of Figure 2, due to the velocity of the aircraft and the wind. Upon reaching the release device 5, the traveler ring 7 will continue in its sliding movement thereover and strike the cam portion 15 of the free end 10 thereby depressing the same and moving it toward the free end 12, as shown in the full lines of Figure 2. In order to obtain this depressing action, it will be understood that the distance normally between the outer side of the cam portion 15 of the free end 10 and the outer side of the free end 12 is greater than the inner diameter of the traveler ring 7. When the free end 10 is depressed or forced toward the opposed free end 12, it will be seen that the enlarged portion 13 carried thereby is moved inwardly or below the outer surface of the U-shaped member 18, as shown in Figure 2, thus permitting the traveler ring 7 of the spent target to pass off the end of the release device 5 and the spent target then falls to the earth. After the traveler ring 7 of the replacement or new target has passed over the cam portion 15 of the free end 10, this free end will move outwardly and away from the free end 12 due to the resiliency thereof and again assume its normal position against the inner side of the U-shaped member 18 with the enlarged portion 13 projecting therebeyond, as shown in the broken lines of Figures 2. The traveler ring 7 of the new target will continue to slide over the release device and pass over the U-shaped member 18 until the inner or upper side of the traveler ring 7 strikes the enlarged portion 13 of the free end 10. The opposite or lower side of the traveler ring 7 will continue to move up over the arcuate-shaped portion 16 of the free end 12 until the outer side thereof strikes the finger-like portion 17 carried thereby during which time the target 8 will open up from its original bundled form to the expanded form as indicated at the extreme right at 8 in Figure 1 of the drawing. It will be seen that the cooperation of the enlarged portion 13 and the finger-like portion 17 with the traveler ring 7 prevents any further movement of the same over the release device 5 and it is releasably held thereon until it is desired to replace this target with another new target. It is the purpose of the cam portion 20 on the free end 12 to direct the side of the traveler ring to the outer side of the U-shaped portion 18. It will be understood that the impact of the traveler ring, when it reaches its position on the end of the release device, is absorbed by the combination of the longitudinal resiliency of the arm 10 and the cantilever resiliency of the finger-like portion 17 of the free end 12.

As a result of my invention, it will be seen that there is provided a release device which will tend to neither rotate nor whip when in use due primarily to the greatly reduced weight of the body member. In other words, the tow cable, the release device and the target will always be in alignment with each other so as to provide a straight line tow, so that all the forces exerted on the release device are longitudinal and absorbed by

the release device itself. In my improved release device, it will be seen that the release of the spent or used target is positive due to the depression of the free member 10 together with the enlarged portion 13 carried thereby, as caused by the traveler ring pressure on the cam surface 15 thereof and the under drag on the lead cable 6 of the new target, as caused by tow resistance.

While I have shown and described one specific embodiment of my invention, it will be understood that this embodiment is merely for the purpose of illustration and description and that various other forms may be devised within the scope of my invention, as defined in the appended claims.

I claim:

1. In apparatus for exchanging an aerial target towed by an aircraft tow line for a replacement target with each target having a traveler ring arranged therewith, a target release device secured to the end of the tow line comprising a resilient metallic member bent upon itself so as to provide a longitudinally extending body member of generally U-shape, the tow line being attached to the closed end of the U-shaped body member, the opposed arms of said body member being normally spaced from each other, the traveler ring of each replacement target being adapted to slide over said body member longitudinally thereof, means arranged on the ends of said opposed arms which cooperate with the traveler ring of a target for holding the same releasably thereon, intermediate portions of the two arms of the body member being so shaped that the traveler ring of a replacement target must force the ends of the arms of the body member together from their normal spaced relationship as such ring travels thereover carrying a replacement target but allows separation of the ends of the arms after it has passed over such intermediate portions of the arms, whereby the target being towed is released and the replacement target is coupled to the tow line.

2. The combination as defined in claim 1, wherein the resilient metallic member is made of wire.

3. In apparatus for exchanging an aerial target towed by an aircraft tow line for a replacement target with each target having a traveler ring arranged therewith, a target release device secured to the end of the tow line comprising a resilient metallic member bent upon itself so as to provide a longitudinally extending body member of generally U-shape, the tow line being attached to the closed end of the U-shaped body member, the opposed arms of said body member being normally spaced from each other, the traveler ring of each replacement target being adapted to slide over said body member longitudinally thereof, means arranged on the ends of the opposed arms which cooperate with the traveler ring of a target for holding the same releasably thereon, portions of said opposed arms intermediate the length thereof being so shaped that when the arms are in their normal spaced relationship the distance between lines drawn parallel to the longitudinal axis of the U-shaped body member and tangent to the outer surfaces of the two arms at such intermediate portion is greater than the distance between two lines parallel to the axis of the body member and tangent to the inner arm contacting surfaces of the traveler ring in the position it assumes when sliding over the body portion of the U-shaped member carrying a replacement target, whereby travel of the traveler ring of a replace-

ment target over such intermediate portion of the arms causes release of the used target and coupling of the replacement target to the tow line.

5. 4. In apparatus for exchanging an aerial target towed by an aircraft tow line for a replacement target with each target having a traveler ring arranged therewith, a target release device secured to the end of the tow line comprising a resilient metallic member bent upon itself so as to provide a longitudinally extending body member of generally U-shape, the tow line being attached to the closed end of the U-shaped body member, the opposed arms of said body member being normally spaced from each other, the traveler ring of each replacement target being adapted to slide over said body member longitudinally thereof, means arranged on the ends of the opposed arms which cooperate with the traveler ring of a target for holding the same releasably thereon, the opposed arms of the body member being so spaced from each other from the closed end of the U-shaped body for a substantial portion of the total length of the body that the traveler ring slips over such body freely when the arms are in their normal spaced position, at least one of the arms having such shape at a portion intermediate its length that the outer surface thereof diverges from the longitudinal axis of the U-shaped body and then converges toward the axis, in a direction away from the closed end of the body, the distance between lines drawn parallel to the longitudinal axis of the U-shaped body member and tangent to the outer surfaces of the two arms at such intermediate portion being normally greater than the distance between two lines parallel to the axis of the body member and tangent to the inner arm contacting surfaces of the traveler ring in the position it assumes when sliding over the body portion when carrying a replacement target, whereby travel of a traveler ring of a replacement target over the intermediate portions of the arms of the body releases the used target and effects coupling of the replacement target with the tow line.
10. 5. In apparatus for exchanging an aerial target towed by an aircraft tow line for a replacement target with each target having a traveler ring arranged therewith, a target release device secured to the end of the tow line comprising a resilient metallic member bent upon itself so as to provide a longitudinally extending body member of generally U-shape, the tow line being attached to the closed end of the U-shaped body member, the opposed arms of said body member being normally spaced from each other, the traveler ring of each replacement target being adapted to slide over said body member longitudinally thereof, a hook-like member extending outwardly from the longitudinal axis of the body member arranged on the end of one of the arms of the body member and an end on the other arm cooperating therewith to hold a traveler ring releasably thereon when the arms are in their normal spaced relationship, portions of the two arms intermediate their length being so shaped that the traveler ring of a replacement target must force the arms of the body member together as it slides thereover carrying a new target but allows separation of the arms after it has passed over such intermediate portions thereof, whereby the target being towed is released from the hook-like member and the replacement target is coupled to the tow line.
15. 6. The combination as defined in claim 5,

wherein the hook-like member on the end of one of the arms consists of an enlarged portion arranged on the outer side of the end of such arm, and the cooperating end on the other arm consists of a portion of such arm bent inwardly and outwardly and having a longitudinally extending finger-like portion arranged on the extreme outer end thereof beyond said hook-like member on the end of the other arm, the traveler ring of a target held by such device fitting over the hook-like member on the first mentioned arm and the finger-like portion on the second mentioned arm.

7. The combination as defined in claim 1, including means for limiting the outward movement of one of said arms of the body member relative to the opposed arm of the body member, said means being adapted to guide said arms in their movement relative to each other.

8. The combination as defined in claim 4, wherein the means arranged on the end of one of the arms which cooperate with the traveler ring of a target for holding the same releasably thereon consists of an outwardly extending hook-like member on the end of such arm to hold the traveler ring of a target when the arms are in their normal spaced position.

9. The combination as defined in claim 4, wherein the arm opposite that whose intermediate portion diverges from the axis of the body and then converges toward the axis, has a portion which diverges from the axis at a point substantially opposed to the point on the first arm where the second arm begins to converge, whereby a traveler ring of a replacement target in traveling over the U-shaped body cooperates with the diverging portions of the two arms to move the two arms together.

10. An apparatus for exchanging an aerial target towed by an aircraft tow line for a replacement target with each target having a traveler ring arranged therewith, a target release device secured to the end of the tow line comprising a resilient metallic member bent upon itself so as to provide a longitudinally extending body member of generally U-shape, the tow line being attached to the closed end of the U-shaped body member, the opposed arms of said body member

being normally spaced from each other, the end of one arm being provided with an enlarged portion arranged on the outer side thereof, and the outer end of the other arm being bent inwardly and outwardly and having a longitudinally extending finger-like portion arranged on the extreme outer end thereof beyond said enlarged portion on the end of the opposed arm, the traveler ring of each replacement target being adapted to slide over said body member longitudinally thereof, the arms being so spaced from each other from the closed end of the U-shaped body to a point intermediate the length thereof that the traveler ring slips over the arms freely when they are in normal open position, at least one arm being so shaped in a portion intermediate its length that its outer surface diverges from the axis of the U-shaped body member and then converges toward the axis of the body, the distance between lines drawn parallel to the longitudinal axis of the U-shaped body member and tangent to the outer surfaces of the two arms at each intermediate portion being greater, when the arms are in their normal spaced relation, than the distance between two lines parallel to the axis of the body and tangent to the inner arm contacting surfaces of the traveler ring of a replacement target in the position it assumes when sliding over the body portion carrying a replacement target, and means attached to that arm of the body which has a finger-like portion at the end thereof close to and cooperating with the enlarged outwardly directed portion on the other arm to support the traveler ring of a target in use, travel of a traveler ring of a replacement target past the intermediate portions of the arms of the body causing the arm provided with the enlarged outwardly directed portion to be pressed toward the longitudinal axis of the body member and consequent retraction of the enlarged outwardly directed portion thereof with respect to the cooperating traveler ring supporting means, whereby the used target is released.

11. The combination as defined in claim 10, wherein the resilient metallic member is made of wire.

ALAN E. BRICKMAN.
